UNITED STATES PATENT OFFICE

LUCIEN KLOPOTOWSKI, OF PARIS, FRANCE

BUOY FOR SAVING THE OCCUPANTS AND THE MATERIAL OF SUBMARINE BOATS

Application filed May 8, 1931, Serial No. 535,972, and in France May 10, 1930.

The principal object of the invention is to provide improved means by which a buoy may be carried exteriorly of the body of a submarine vessel so as to be out of the way and avoid occupying useful space in the interior of the submarine and to effect improvements in means by which the buoy may be entered from within the submarine and released from the submarine and employed thereby for saving life and facilitating escape of persons from the submarine when the latter is submerged.

To this end there may be provided on or above the body of the boat, and preferably within the superstructure of the conning bridge, a convenient lodging chamber for the buoy.

This chamber can also be introduced or provided within the existing apertures serving for the introduction of submarine mines.

With the above and other objects in view, the invention consists in the construction, combination and arrangement of devices hereinafter described and claimed.

On the accompanying drawings several forms of embodiment have been shown, and on this drawing:

Fig. 1 is a longitudinal, schematic section of the submarine boat;

Fig. 2 is a plan view thereof;

Fig. 3 is a vertical transverse sectional view of the deck portion of a submarine provided with a buoy and storing and releasing means for the buoy in accordance with one form of my invention,

Fig. 3a is a similar view of the lower portion of the said storing and releasing means on a larger scale.

Fig. 4 is a similar view showing a modified form of the invention.

Fig. 5 is a similar view of another modified form of the invention.

In Fig. 1 both forms are represented to show the temporary lodgment *a* on the left and the stationary equipment *b* on the right. In the drawings the hull of the submarine is indicated at *c*.

Figs. 3 and 4 show again, more detailed, the temporary and Fig. 5 the stationary form of embodiment for lodging the buoy *g*.

According to Fig. 5, one provides on or above the envelope *d*² of the submarine boat a conical chamber *d*¹ with its larger opening *d*. Within the envelope *d*² of the vessel is provided a manhole, and a central opening 55 for the placement of the anchoring device described hereunto.

In the form of the invention shown in Figures 3 and 4 the hatchway of the submarine is utilized for the reception of the structure forming the lodging chamber *e*³ with its enlarged opening *d*. The buoy *g* is arranged in the said chamber, the diametrically enlarged upper end *d* of the chamber facilitating the emplacement and the release of the buoy, as will be understood. The existing entrance comprises the under part *e* and the cover *e*¹. The latter is now provided with a central opening *e*² which allows the watertight introduction and fixing of the conical seat or chamber *e*³, the upper border whereof is provided with guiding rollers *f*, also shown in Fig. 5. These rollers facilitate the inserting of the buoy *g*. *e*⁴ is the ordinary watertight joint for the now transformed cover *e*¹. 75 Under these circumstances it would be possible to remove rapidly, if desired, the entire buoy lodging chamber *e*³ and all other equipments together with the buoy itself and to reinstate the previous state of art necessary 80 for the introduction of submarine-mines.

According to Fig. 3 the chamber *e*³ is closed at the bottom by means of a closure *r* having a manhole *r'* provided with a hatch *r*², provided with an entrance or manhole. To this center of said closure are attached the devices for anchoring and detaching the buoy *g* which has the usual form and contains the ordinary apparatus and instruments etc. Moreover it is provided in its interior with a watertight winch *m*, on the drum whereof is placed a cable, the other end whereof is attached to a second drum *n* arranged in the inside of the boat, this cable traversing the respective mechanical devices 90 vertically and centrally as indicated by the vertical line *x*.

The hollow bottom *h* of the buoy *g* has a manhole *g*¹, closed by the cover *g*², and it is traversed in its center by a vertical tube *h*¹ 100

with a fungiformed cap h^2 , the rear horizontal face whereof allows the movable hooks h^3 to grasp the extremity of said tube which is fixed in a convenient manner to the buoy. The latter is then maintained in the shown position within the conical chamber or seat e^3 . Within the tube is lodged a hollow slidable rod i , provided at its end with a curved plate i^1 . The rod is continuously under the influence of a spring i^2 which endeavours to push the rod out of the tube h^1 and to bear against a plate k which forms a part of a screwed spindle l^4 which moves within the boss l^3 of toothed wheel l^2 15 gearing with a second wheel l^1 which can be manually rotated by means of a hand wheel l from the interior of the boat.

The under end of each hook h^3 is articulated to the plate k while a link j connects 20 it to the casing j^1 fixed in a suitable manner to the cover.

By screwing out the spindle l^4 , the hooks are progressively detached from the cap h^2 and at the same time the spring i^2 is compressed, so that the buoy is pushed upwards. 25 Water is then entering the intermediate room and said buoy can rise to the surface under the hydrostatic buoyancy as soon as the cable is released from the one or the other of the drums m or n .

Fig. 4 shows a modified form of embodiment, and wherein the same letters indicate similar parts.

The outer bottom is provided with four 35 equidistant rails o provided with rollers which facilitate the entrance of the buoy into its seating. The grasping device is moved by means of screw spindle l^4 which turns within a screw l^3 lodged within the box j^1 .

40 In Fig. 5 the grasping device is again directed by means of a central screw-spindle and a hand wheel.

I claim:

1. A vessel having a chamber arranged 45 exteriorly of its hull and communicating with its interior, a buoy detachably arranged in said chamber and having a tube projecting from its bottom, said tube having recesses in its exterior side, a revoluble member having a bearing in the bottom of said chamber and provided with an internally threaded opening, a screw engaged in said threaded opening, means mounted on said screw and including hooks engaging the recesses of said 50 tube, said hooks being disengaged from said tube to release the buoy by axial movement of the screw imparted thereto by the threaded opening of the revoluble member when the latter is turned, and means in the tube active 55 when the tube is detached by the hooks to impart launching thrust to the buoy to disengage the latter from its storage chamber.

2. Apparatus as claimed in claim 1, in 60 which the means to impart launching thrust 65 to the buoy comprises an inner tube arranged

in the lower end of the first named tube and bearing on the screw and a normally compressed coiled spring in the first named tube and bearing between the upper end thereof and the upper end of the inner tube.

In testimony whereof I have hereunto set my hand this 24 day of April A. D. 1931.

LUCIEN KLOPOTOWSKI.
